William H. Whitney, Cranston, R. I.

Application May 4, 1954, Serial No. 30,325

Term of patent 7 years

(Cl. D29—2)

To all whom it may concern:

Be it known that I, William H. Whitney, a citizen of the United States of America, residing at Cranston, in the county of Providence and State of Rhode Island, have invented a new, original, and ornamental Design for a Fez Clip, of which the following is a specification, reference being had to the accompanying drawing, forming a part hereof.

Fig. 1 is a front elevation view of a fez clip embodying my new design.

Fig. 2 is a side elevation view thereof with the spring clip removed; and

Fig. 3 is a bottom plan view thereof.

I claim:

The ornamental design for a fez clip, substantially as shown.
